FOLDING CHAIR

Fred P. Danzer, Racine, Wis., assignor to Gold
Medal Folding Furniture Co., Racine, Wis.

Application October 10, 1932. Serial No. 637,000

2 Claims. (Cl. 155—117)

This invention pertains to folding chairs, and more particularly to what are commonly known as adjustable reclining chairs.

Heretofore, in chairs of the foregoing character provided with arms, numerous pivotal connections and complicated link arrangements have been employed to permit desired folding of the arms with the chair, and to compensate for folding and adjustment of the chair.

10 The foregoing structure is necessarily costly in manufacture, requires an awkward operation in collapsing and interfolding the chair, presents an extremely weak structure, and, lastly, but highly important, such arms make occupancy and egress of the chair extremely awkward, particularly when the chair is provided with the conventional foot-rest.

It is therefore the primary object of the present invention to overcome the foregoing objections by the provision in a conventional folding chair of an extremely simple, inexpensive and durable arm structure, which eliminates links and a multiplicity of pivotal connections, and enables the arms to be readily swung out of the way for convenient occupancy or egress of the chair, and also facilitates folding or setting up of the chair.

Incidental to the foregoing, a more specific object resides in the provision of a folding chair, in which the arms are pivotally connected to the adjustable support, and are freely supported upon projections carried by the back frame, whereby they may be readily swung out of the way when desired, and yet maintain a substantially horizontal position, regardless of the adjusted position of the chair.

With the above and other objects in view, which will appear as the description proceeds, the invention resides in the novel construction, combination and arrangement of parts, substantially as hereinafter described and more particularly defined by the appended claims, it being understood that such changes in the precise embodiment of the herein disclosed invention may be made as come within the scope of the claims.

45 In the accompanying drawing is illustrated one complete example of the physical embodiment of the present invention constructed according to the best mode so far devised for the practical application of the principles thereof.

50 In the drawing:—

Figure 1 is an elevation of a conventional foldable reclining chair, with the invention incorporated therein.

Figure 2 is a plan view, with parts broken away and in section, and

Figure 3 is a detail section of a modification of the invention.

Referring now more particularly to the accompanying drawing, the numeral 1 designates a back frame, to which the seat frame 2 is pivotally connected by rivets 3, or any other suitable connection. The back frame 1 comprises the usual side rails 4, connected at their ends by the transverse braces 5, while the seat frame 2 likewise comprises the side rails 6 connected at their respective ends by the transverse braces 7.

Pivotally connected to the seat frame by the rivets 8 is an adjustable support 9, which includes the arms 10, connected at their lower ends by a transverse bar 11, which in the setup position of the chair engages the spaced notches 12 provided in the upper edges of the seat rails 6. As indicated in dotted lines on Figure 1, a strip of fabric or canvas 13 is connected to the top transverse braces 5 and 7, respectively, thus forming the seat and back rest.

The foregoing structure, which has been illustrated and described in some detail, is conventional, and, therefore, forms no part of the present invention other than in the combination as hereinafter claimed, it being understood that the invention may be applied to other conventional types of folding chairs.

In its preferred form, the invention essentially consists of a pair of arm rests 14, pivotally connected to the outer sides of the supporting arms 10 intermediate their ends, and in order to support the arms in substantially horizontal position, when the chair is set up, the back rails 4 are provided with pegs or projections 15, which normally engage the arm rests 14 intermediate their ends. As best shown in Figure 2, the outer ends of the arm rests are enlarged inwardly to provide the desired support for the arms of the occupant, and here it may be explained that the enlarged portions of the arm rests are spaced a sufficient distance from the pivoted ends of the arms so as to clear the pivoted ends of the supporting arms 9 as the arm rests are swung rearwardly. Also, inasmuch as the inner edge of the enlarged portion of the arm rest terminates in alignment with the outer face of the back rails 4, the arm rests will likewise clear the back rails when swung on their pivots.

From the foregoing explanation, taken in connection with the accompanying drawing, it will be readily seen that an extremely simple, inexpensive and durable arm structure has been provided for folding chairs, which is easily manipulated in collapsing and unfolding the chair, and

which may be readily swung out of the way to facilitate occupancy or egress of the chair, this being extremely awkward where rigid arms are employed, particularly in instances where the 5 chair is provided with a conventional foot-rest, such as indicated by dotted lines in Figure 1.

It will further be appreciated that the present invention permits ready adjustment of the chair, by shifting of the support 9 into the various 10 notches provided in the seat rails 6, and at the same time the arm rests maintain a substantially horizontal position, inasmuch as any adjustment of the chair simultaneously raises or lowers both the pivotal connections of the arm rests and the 15 supporting backs 15.

In the modification illustrated in Figure 3, the arm rest 14 is pivotally connected in a clevis 16, which may be pivotally or rigidly connected to the adjacent supporting arm 9. In this form of 20 the invention the arm 14 may be swung either horizontally or vertically, suiting the convenience of the occupant of the chair. Thus it will be seen that the same results and advantages heretofore described may be accomplished in various ways 25 without departing from the invention, the salient feature of which resides in the elimination of supporting links for the arms, and providing for

moving the arms independently of any adjustment of the chair.

I claim:—

1. In a folding chair comprising pivotally connected back and seat rails and an adjustable support pivotally connected to the back rails adjustably engaged with the seat rails, a pair of arm rests pivotally connected to the outer sides of said adjustable support, the outer ends of said arm rests being enlarged inwardly, the enlarged portions clearing the pivoted ends of said support and said back rails when swung on their pivots, and means carried by said back rails for slidably supporting the free ends of said arm rests. 80

2. In a folding chair comprising pivotally connected back and seat rails and an adjustable support pivotally connected to the back rails adjustably engaged with the seat rails, a pair of arm rests pivotally connected to the outer sides of said adjustable support, the outer ends of said arm 85 rests being enlarged inwardly, the enlarged portions clearing the pivoted ends of said support and said back rails when swung on their pivots, and projections carried by said back rails for slidably supporting the free ends of said arm 100 rests. 90
